[57] **CLAIM**

The ornamental design for a disposable bag holder, as shown and described.

DESCRIPTION

FIG. 1 is a perspective view of a disposable bag holder showing my new design;

FIG. 2 is a front elevational view thereof;

FIG. 3 is a rear elevational view thereof;

FIG. 4 is a left side elevational view thereof, the right side being a mirror image of that shown;

FIG. 5 is a vertical cross-sectional view thereof, taken along line 5—5 of FIG. 2;

FIG. 6 is a top plan view thereof;

FIG. 7 is a bottom view thereof; and

FIG. 8 is a reduced perspective view thereof, the broken-line showing of the disposable bag being shown for illustrative purposes only and forming no part of the claimed design.
